B. WARNECKE

POULTRY ROOST

Filed Sept. 2, 1921

B. Inventor: Warnecke,

By Wallace R. Lane, Attorney

UNITED STATES PATENT OFFICE.

BERNARD WARNECKE, OF BRESEE, ILLINOIS.

POULTRY ROOST.

Application filed September 2, 1921. Serial No. 497,862.

To all whom it may concern:

Be it known that I, BERNARD WARNECKE, a citizen of the United States, residing at Breese, Illinois, have invented certain new 5 and useful Improvements in Poultry Roosts, of which the following is a specification.

Among the objects of my invention are to improve upon the construction of poultry roosts; to make such roosts as near vermin 10 proof as possible; to so construct such roosts that the tendency thereof, when in use, will be to destroy vermin; to construct such roosts with interchangeable parts for summer and winter use; to so simplify the construction of such an article that it can be 15 easily put up by anyone with a minimum of work and in a short time; and such further objects, advantages and capabilities as will later more fully appear.

20 My invention further resides in the combination, construction and arrangement of parts illustrated in the accompanying drawing, and while I have shown therein a preferred embodiment I desire the same to be 25 understood as illustrative only and not as limiting my invention.

In the drawing attached hereto and forming a part hereof:

Fig. 1 is a perspective view of a construction embodying my new improvements,

30 Fig. 2 is a fragmentary vertical section along the plane indicated by the line 2—2 Fig. 1,

Fig. 3 is a fragmentary elevation to show 35 the rocking of certain of the roosts,

Fig. 4 is a fragmentary perspective view of another mode of assembling my device.

Referring more in detail to the annexed drawing numeral 1 designates the side or 40 supporting members, 2 the suspending members by means of which this construction is supported from a rafter, joist or similar elements 3. The side or supporting members 1 are adjustably connected by means of rods 4, 45 having adjacent their ends nuts for varying the distance between the side members. Projecting from one edge of each of the members 1 are a plurality of brackets 5, notched at their upper edges as shown for the reception 50 of the angular shaped ends 6 of the roosts 7, preferably made of metal, either hollow or solid, the former being preferred.

For winter use any desired number of 55 these metallic roosts may be replaced by wooden roosts 8 resting on and secured to the brackets 5 by suitable means 9 such as

clips, wire, or the like. During the cold weather these wooden roosts are much more comfortable for the chickens than are the metallic roosts 7, which are very cold for 60 the chickens feet to rest on in winter. It is therefore considered very desirable to replace a majority of the metallic roosts 7 with wooden, or the like, roosts 8 for use during the coldest weather. However, during 65 the warm weather when lice and such vermin tend to hide in cracks and crevices in the roosts it is preferable to have the rockable roosts 7 used instead of the fixed roosts 8, so that when the chickens stand on 70 the roosts and rock them in their attempt to balance, the vermin will become crushed between the end 6 and the bottom and sides of the notches in the brackets 5. Not only does this construction reduce by a great 75 number the hiding places for vermin, but also, many of the vermin themselves are killed by the rocking of the roosts in their supports.

The method of applying roosts 8 shown in 80 Fig. 4 is considered preferable to that shown in Fig. 1 because of the ease with which the same may be applied and removed. Pins 10 are passed through boards 8, either inside or outside the members 1 so as to prevent longitudinal sliding of the boards. It will be 85 obvious that with this arrangement it will be very easy to put the boards in position, replacing the roosts 7.

Having now described my invention, I 90 claim:—

1. In a poultry roost construction, notched side supports, and a roost having crushing surfaces resting loosely in notches capable of moving and permitting the roost to rock 95 when pressure is applied to the roost.

2. In a structure of the character described, supporting members and a rockable non-rotatable roost resting loosely on the supporting members and capable upon pressure to the roost of rocking on said supporting members.

3. In a structure of the character described, a pair of supporting members having roost supporting projections along their upper edges, said projections being provided with notches for the reception of roosts, metallic roosts having angular shaped ends securely and loosely resting in the notches and capable of rocking slightly therein upon pressure being applied to the roost, and staying members adjustably holding the sup-

porting members rigidly with respect to each other.

4. In a structure of the class described, spaced supporting members having roost supporting portions provided with notches for the reception of roosts, having crushing surfaces, roosts loosely resting in said notches and capable of a limited amount of rocking movement by the shifting of the crushing surfaces within the notch, and means for adjustably holding the supporting members in spaced relation.
5. In a structure of the class described, spaced supporting members having roost

supporting portions, roosts on said portions, 15 said portions and roosts having cooperable means for permitting a limited rocking of the roosts, and pendulous members connected at the lower ends thereof to said supporting members.

20 In witness whereof, I hereunto subscribe my name to this specification in the presence of two witnesses.

BERNARD WARNECKE.
